UNITED STATES PATENT OFFICE.

WILLIAM OVERTON RUTHERFORD, OF JACKSON, TENNESSEE.

LINE HOLDER.

Application filed December 1, 1922. Serial No. 604,334.

To all whom it may concern:

Be it known that I, WILLIAM O. RUTHERFORD, a citizen of the United States, residing at Jackson, in the county of Madison and State of Tennessee, have invented new and useful Improvements in Line Holders, of which the following is a specification.

In masonry, it is necessary that the corners of buildings be first partly erected and that a line be stretched between the courses of brick or stone so that the intermediate bricks or stones will be laid at the same level as that at the corners. Ordinarily, comparatively sharp implements, such as common nails have the line wound therearound and one nail is inserted in the mortar at one corner of a building construction and the other inserted in the mortar between courses at the other corner of the construction. The line must be drawn taut, and to do this it is necessary that one of the mechanics at a corner of the building turn the nail or similar implement so that the line will be tightly wound therearound.

It is the object of this invention to obviate the inconvenience of repeatedly winding a masonry guide line when the same is raised at the corners of a building construction.

It is a further object to produce a means for this purpose in which the ends of a masonry guide line can be drawn taut without necessitating the winding of the line on the means that enter between the courses at the corners of masonry.

It is a still further object to produce a masonry line holding device that shall be of an extremely simple construction, cheaply manufactured and marketed, and thoroughly efficient for the purpose devised.

To the attainment of the foregoing, and other objects which will present themselves as the nature of the invention is better understood, reference is to be had to the drawing which accompanies and which forms part of this application.

In the drawing:

Figure 1 is a view illustrating the application of the improvement.

Figure 2 is a perspective view of one of the line holders with a sufficient portion of a line thereon to illustrate the manner in which the line can be drawn taut without being wound on the holder.

The body of my improvement is preferably formed from a strand of suitable steel wire to provide a shank 1 having a pointed

end. The wire member, at its opposite end is rounded upon itself and extended in a line parallel with that of the shank, as indicated by the numeral 2. The extended portion has its end rounded upon itself and is extended over the portion 2, as indicated by the numeral 3. The end of the portion 3 is flared outwardly to provide a jaw 4. In order to cause the jaw 4 to frictionally contact with the extension 2, I arrange around the portions 2 and 3, a suitable distance inward of the jaw 4, a metal loop 5.

To hold the portion 2 against the shank 1 there is preferably soldered thereto an extension on the outer end of a coiled wire 6 that surrounds the shank 1. The opposite or inner end of this coil is bent outwardly and extended in the direction of the pointed end of the shank to provide a hook 7.

In practice, one end of the line 8 is received between the jaw 4 and the portion 2 of one of the devices and is from thence directed between the shank 1 and the hook. This holder is inserted in the mortar between courses at one corner of a building. The line is extended to be received between the hooks 7 on the shank 1 of the second holder at the opposite corner and is from thence drawn into the jaw 4. Any slack in the line 8 may be readily taken up by drawing upon either end of the said line, and it is thought that the foregoing description when taken in connection with the drawings will fully set forth the construction and advantages of the improvement to those skilled in the art to which such inventions relate without further detailed description.

Having described the invention, I claim:

1. A line holder for the purpose set forth constructed from a single strip of wire comprising a shank having a pointed end, rounded at its opposite end and inwardly extended to contacting engagement with the shank and from thence further rounded upon itself and extended to provide a spring jaw in contact with the first extension, said jaw having its end rounded outwardly, means between the jaw and extension for causing the jaw to exert a spring tension against the extension, and a hook on the shank disposed inward of the jaw.

2. A line holder for the purpose set forth constructed from a single strip of wire comprising a shank having a pointed end, rounded at its opposite end and inwardly

extended to contacting engagement with the shank and from thence further rounded upon itself and extended to provide a spring jaw in contact with the first extension, said jaw having its end rounded outwardly, means between the jaw and extension for causing the jaw to exert a spring tension against the extension, a wire coiled around

the shank having an extended loop arranged around the referred to extension and soldered or otherwise connected thereto, and the opposite end of the coil being offset in the direction of the shank to provide a hook, for the purpose set forth.

In testimony whereof I affix my signature.

WILLIAM OVERTON RUTHERFORD.
